UNITED STATES PATENT OFFICE.

MARSHALL H. JACKSON, OF CHICAGO, ILLINOIS.

BOOK LOCK.

Application filed October 21, 1927. Serial No. 227,638.

This invention relates to book locks and has among its objects the provision of a simple locking device that may be readily applied to the current forms of books, particularly loose leaf books, so as to prevent unauthorized opening of the same.

There are at present available books, such as private ledgers and the like, in which the book covers are provided at their edges with a built-in locking device permitting the owner of the book to hold the same locked and preventing others from having access to the contents thereof.

Very often it is desired to lock a book, the covers of which have not a built-in locking device. By means of the device of the present invention any of the ordinary books may be transformed into a locked book by the application of a very simple locking strap arranged to be anchored between the book covers and a locking clamp arranged to embrace and hold together the open edges of the covers, the clamp having a suitable locking connection with the projecting portion of the strap.

The invention will be best understood from the following description of an exemplification thereof, reference being had to the accompanying drawings, wherein

Fig. 1 is a perspective view of a book provided with a locking device according to the invention;

Fig. 2 is a transverse sectional view through Fig. 1 along the line II—II;

Fig. 3 is a transverse sectional view through a book provided with a locking device embodying a modification of the invention;

Fig. 4 is a perspective view of a portion of a book illustrating the application of a supplemental locking device for holding the end edges of a book locked;

Fig. 5 is a fragmentary horizontal section through Fig. 4; and

Fig. 6 is a vertical sectional view through a locking clamp adjustable for books of different thicknesses.

In Figs. 1 and 2 there is illustrated for the purpose of exemplifying the invention a loose leaf book of familiar form in which a package 1 of substantially rectangular sheets or leaves is clamped at one side, constituting the back 3 of the book, between two rigid covers 4 and 5. The book illustrated in the drawing is of the loose leaf type, the leaves being held on posts 6 which are suitably locked in anchor-

ing brackets 7 in the rear edges of the two covers 4 and 5.

It is often desired to arrange such books so as to permit locking of the open edges of the covers to prevent unauthorized inspection of the contents of the book. Heretofore, as far as I am aware, special locking or clamping devices had to be built in or otherwise permanently embodied in the covers of the book in order to permit locking thereof. According to the present invention, any book of the type illustrated may be transformed into a locked book without making any changes in the arrangement of the book and without requiring the provision of special clamping devices that are permanently connected or fastened to the covers or other parts of the book.

As shown in the drawing, I provide to this end a sheet-metal strap 11 having its rear end 12 bent at an angle of 90° so as to overlap the rear edges of the leaves, and its front end formed into a loop or staple member 13 arranged to project in front of the edges of the book leaves. A U-shaped locking clamp or yoke 15 adapted to fit over and hold together the open edges of the book covers 4 and 5 has a perforation or slot 16 adapted to fit over the loop member 13 of the strap so as to permit insertion of the clamp 15 over the book edges with the staple member 13 projecting through the slot 16 in front thereof. A small padlock 17 may then be passed through the opening of the loop member 13 so as to lock the clamp 15 in place, preventing its removal from over the edges of the book.

The clamp 15 is preferably made from rigid material, such as brass or steel, that will not readily bend open. The locking clamp 15 is preferably so shaped as to conform to the contour of the closed book providing a special holding groove fitting over each cover edge.

The anchoring strap 11 may be either narrow, as shown in Figs. 1 and 2, or it may conform in size to a full leaf or sheet of the book and have perforations fitting over the posts 6 so as to be placed between the leaves of the book just as an additional leaf. In the modification of the invention illustrated in Figs. 1 and 2 the strap is of relatively narrow width and is intended to be inserted over the top leaves of the book directly underneath the upper cover 4, and in order to provide a more convenient connection between the loop member 13 of the strap and the clamp 15, the

front end of the strap is offset downwardly so as to bring out the loop approximately at the middle of the leaf package 1.

In most cases a simple downwardly bent portion 12 in the rear of the strap 11 will be sufficient to hold the strap firmly anchored at the back of the book, but, if desired, the rear end portion may be formed so as to give any desired degree of anchorage, for instance, by providing a perforation in the strap fitting over a post 6 that holds the leaves together. Such construction is shown in Fig. 3, wherein an anchoring strap 11' has its rear end perforated to fit over the post 6 of the book, the front end of the strap projecting into the slot 16 of the locking clamp 15, like the arrangement of Figs. 1 and 2.

The locking arrangement of my invention is also adapted to be applied for locking the upper or lower edge of the book. Such arrangement is shown in Figs. 4 and 5 wherein an anchoring strap 20, resembling the shape of a rectangular triangle, is anchored between the rear edges at the lower end of the book and has a loop member 21 projecting in front of the lower edge of the leaf package and is arranged to fit into a locking clamp 15' similar to the clamp 15 described above. The locking clamp may be locked in place by a 30 padlock inserted through the loop 21. Instead of a padlock locking connection between the loop members 13, any other locking connection may, of course, be used, for instance, the lock may be embodied directly in the locking clamp 15.

The locking clamp may be also arranged to be adjustable for books of different thicknesses, as shown in Fig. 6, the clamp consisting of two parts 25, 26 adapted to fit over the book edges, and telescopic or overlapping portions 27, 28 extending towards and fitting into each other, the overlapping portions being provided with slots 29 through which the loop member of the anchoring strap may be inserted. The slots 29 in the overlapping portions of the upper and lower clamping members, 25 and 26, respectively, are arranged to register so that the loop member 13 may be inserted therethrough to provide different thicknesses of the clamp.

The invention is susceptible of many other modifications that will suggest themselves to those skilled in the art and it is, accordingly, desired that the appended claims be given a broad construction commensurate with the scope of the invention within the art.

I claim:

1. The combination with a book having a pack of leaves and a pair of relatively rigid

covers, of a locking device therefor comprising a loose strap anchored between the covers, a loose clamp adapted to fit over and hold together the open edges of the covers, and a locking connection between the strap and the clamp.

2. The combination with a book having a pack of leaves and a pair of relatively rigid covers clamped to one side of said pack, of a locking device therefor comprising a strap anchored between the covers at the back edges of the sheets and having a portion projecting in front of the open edges of the leaves, a loose clamp adapted to fit over and hold together the open edges of the covers, and a locking connection between the projecting portion of the strap and said clamp.

3. The combination with a loose leaf book having a pack of loose leaves and a pair of binder covers having means for clamping said pack of leaves at the back edge thereof, of a locking device therefor comprising a strap anchored between the covers at the back edge of said leaves, a clamp adapted to fit over and hold together the open edges of the covers, said strap having a projecting portion extending in front of the open edges of the leaves, and a locking connection between said projecting portion and said clamp.

4. The combination with a book having a pack of sheets, a locking strap bound with the sheets, a clamp adapted to embrace free edges of said sheets, and means for locking said clamp to said locking strap.

5. The combination with a book having a pack of sheets, an anchoring strap bound with said sheets, an extensible clamp adjustable for different thicknesses embracing said sheets at the outer edges thereof, and means for locking said clamp to said strap.

6. The combination with a book having a pack of leaves and a pair of covers, of a locking device comprising a strap anchored between the covers, a clamp adapted to engage and hold together the open edges of the covers and a locking connection between the strap and the clamp.

7. The combination with a book having a pack of leaves and a pair of covers therefor, of a locking device comprising a strap anchored between the covers, a clamp adapted to engage and hold together the open edges of the covers, said clamp being adjustable for various thicknesses, and a locking connection between the strap and the clamp.

In testimony whereof I have hereunto subscribed my name.

MARSHALL H. JACKSON.
